UNITED STATES PATENT OFFICE.

FRANCIS H. HOWARD, OF HOUSTON, TEXAS.

CONCRETE CONSTRUCTION.

1,072,230.

Specification of Letters Patent.

Patented Sept. 2, 1913.

Application filed December 19, 1912. Serial No. 737,626.

To all whom it may concern:

Be it known that I, FRANCIS H. HOWARD, a citizen of the United States, residing at Houston, in the county of Harris and State of Texas, have invented certain new and useful Improvements in Concrete Construction, of which the following is a specification.

My invention relates to new and useful improvements in concrete construction.

The object of the invention is to provide a system of constructing buildings such as dwelling houses and other buildings wherein the parts are formed of concrete, and comprehends also an improved method of assembling and uniting the different parts.

As is well-known, in the construction of concrete buildings the ordinary solid concrete block is now commonly used, and when used, the walls of the building when completed will be substantially of solid concrete, and will not only be unnecessarily ponderous, but will also absorb moisture and keep the building damp.

The walls of a building constructed in accordance with the present invention will not only have no unnecessary weight, but will be formed double with an air space between the double walls, thus preventing the absorption of moisture and keeping the building dry. The parts of the wall and building are also secured together by means of simple and secure joints, which have been designed with the view of securing a strong structure, and at the same time one which may be easily and cheaply constructed.

With the above and other objects in view, the invention has particular relation to certain novel features of construction, an example of which is given in this specification and illustrated in the accompanying drawings wherein:

Figure 1 is a side elevation of a portion of the wall of a building erected in accordance with the present invention. Fig. 2 is a vertical sectional view of said wall taken on the line A—A of Fig. 1. Fig. 3 is a vertical sectional view of the wall taken on the line B—B of Fig. 1. Fig. 4 is a transverse sectional view of said wall taken on the line c—c of Fig. 1. Fig. 5 is a side elevation of one of the wall studdings. Fig. 6 is a sectional end view thereof. Fig. 7 is a sectional end view of one of the corner studdings. Fig. 8 is a side elevation of one of the wall plates or slabs. Fig. 9 is a longi-

tudinal sectional view thereof. Fig. 10 is an end view thereof. Fig. 11 shows a fragmentary view of the joint formed by the abutting ends of the wall slabs with the upper end of the wall studding, and Fig. 12 shows a fragmentary view of the union of an upper floor, of a building having more than one floor, with the walls of the building.

Referring now more particularly to the drawings wherein, like numerals of reference designate similar parts in each of the figures, the numeral 1 designates a base formed of a timber of any suitable dimensions which is placed in the excavation for the foundation, and which supports the studding 2, forming the frame work of the structure. These studdings are placed at the desired distance apart of this base, and extend vertically therefrom, and are fixed in their position, relative to each other, by means of metallic rods 3, which extend therethrough. These rods have nuts 4 threaded thereon, which abut against the sides of the studding, and by turning said nuts the studding may be adjusted relative to each other on the rods, and the rods are located near the upper and lower extremities of the studding, so that said extremities may be correspondingly adjusted. When the studding has been placed in position the base 1 and the lower ends of the studding are surrounded by a mass of concrete 5, which is poured into the excavation in its plastic state, and the studding are then adjusted to their desired position and the concrete allowed to harden, thus forming a solid base in which the lower ends of the studdings are embedded, and in which said studdings become firmly fixed.

Each side of each of the wall studdings has lengthwise extending grooves 6 near the outer and inner edges thereof, respectively. The inner sides of these grooves are abrupt, and the outer sides thereof are sloping, as particularly shown in Figs. 4 and 6.

The numeral 7 designates one of the wall slabs, of which the walls proper are formed. These slabs may be made of any desired width as may be found most practical, and the ends thereof are shaped to conform to the shape of the grooves 6, in which said ends are designed to fit. In placing the slabs in position one end of the slab is first inserted in one of the grooves of the studding and the other end thereof is then

brought into alinement with the corresponding groove of the other studding, and the slab is then moved lengthwise until the last mentioned end is brought to rest in its corresponding groove, and in position so that the space between the ends of the slabs and the bottom of their corresponding grooves will be equal, and the length of the slab is such that, when in position the respective ends thereof will engage against the respective outer sides of said grooves, and inter-lock the slabs with the studding. The corner studding 8, shown in Figs. 4 and 7, in cross section, are L-shaped, so as to conform to the corners of the structure, and are provided with suitable grooves similar to the grooves 6, of the studding 2, for the reception of the ends of the wall slabs 7. When the slabs 7 have been placed in position as above described, the space left between the ends of the slabs and the bottom of the grooves are then filled with cement so as to form perfect joints to hold the slabs in position. The space between the double walls thus formed is then filled with concrete 9 up to the level of the ground surface as shown in Figs. 2 and 3. When the wall has been built up to the floor line, a thick concrete slab 10 is then placed in position on the wall, which extends entirely therearound, and which spans the space between the double wall and is shouldered down so as to extend down a distance between said walls, and the inner edge of this slab extends inwardly beyond the inner side of the wall forming a ledge for the support of the floor sills 11. This slab serves also as a base upon which the portions of the walls thereabove rest. Suitable window casings 12 may be secured between the studdings at the places desired, and interlocked therewith as hereinbefore described, the bottom of each casing being formed of a thick concrete slab 13 of any desired length, which spans the wall and is shouldered down between the sides thereof, as in the case of the slab 10. The abutting ends of the slabs 7 forming the upper tier are shouldered underneath, leaving a space 14, for the reception of the upper ends of the studding as shown in Fig. 11, a cap slab 15, formed of concrete, and which spans the double walls and is shouldered down between the side thereof in the same manner as the slab 10, extends entirely around the top of the wall. Mounted upon this slab is a narrow double wall, section 16, which is filled between with concrete 17, forming a firm base for the sill 18, which supports the joists 19 and rafters, 20.

In case a building of more than one story is constructed, the upper floors are to be formed of concrete, and are united and made integral with the concrete 17 in the manner shown in Fig. 12.

The studding and slabs and other parts which span the double wall of the structure should be composed of water-proof cement, so that a minimum amount of moisture will be absorbed by the walls, and the building will thus be kept dry. 70

The studdings 2 and 8 are reinforced by steel rods 22, running lengthwise thereof, and arranged at a suitable distance apart, and likewise the slabs 7 are reinforced by steel rods 23, extending lengthwise thereof, and arranged at a suitable distance apart and connected by cross-rods 24, also formed of steel. 75

When the wall has been completed the outer and inner sides thereof may be coated with plaster 21 which will give the same a finished appearance, and will render the joints and seams thereof invisible. 80

What I claim is:—

1. A construction of the character described, consisting of up-right studding arranged at a suitable distance apart, rods extending through the studdings and having adjustable securing members thereon which abut against each studding on each side and by means of which said studdings may be adjusted and fixed in position relative to each other, and a double wall formed of slabs spaced apart, each end of each slab interlocking with the studding, and being held into position thereby. 90

2. A construction of the character described, consisting of studding arranged at a suitable distance apart, rods extending through the studdings and having adjustable securing members thereon which abut against each studding on each side and by means of which said studdings may be adjusted and fixed in position relative to each other, the sides of the studding facing each other, having corresponding lengthwise grooves and wall slabs whose ends are shaped to conform to the shape of said grooves, the opposite ends of said slabs fitting into the corresponding grooves of said studding. 100

3. A construction of the character described, consisting of studding and means engaging therewith for adjusting said studding and fixing the same in position, wall slabs spaced apart so as to form a double wall, each of which interlocks with the studding so as to hold said slabs in position, and a wall slab spanning the double wall and shouldered down so as to extend a distance between said walls, said slab extending along the wall and the inner edge thereof extending beyond the inner side of said wall. 115

4. A construction of the character described, consisting of a concrete base, and reinforced concrete studding whose lower ends are embedded in said base, rods extending through the studdings and having adjustable securing members thereon which abut 120

130

- against each studding on each side and by means of which said studdings may be adjusted and fixed in position relative to each other, each side of each studding being provided with two lengthwise extending grooves spaced apart, the grooves of each studding being arranged in a corresponding position to the grooves of the facing side of the other studding, and wall slabs whose ends are shaped to conform to said grooves and fit into the corresponding grooves of the studding so as to form a double wall.
5. A construction of the character described, consisting of a concrete base and concrete studding whose lower ends are embedded therein, a means engaging with the studding and upon which said studding are adjustable, for fixing the position of the studding relative to each other, and wall slabs extending from one studding to another and spaced apart so as to form a double wall and whose ends dovetail with the studding.
- 25 6. A construction of the character described, consisting of a concrete base and a concrete studding whose lower ends are embedded therein, a means engaging with the studding and upon which said studding are adjustable for fixing the position of the studding relative to each other, wall slabs extending from one studding to another and spaced apart so as to form a double wall and whose ends are interlocked with said studding and a slab fixed in the wall and extending therearound, one of whose edges projects from the wall and forms a supporting ledge, said slab being shouldered down so as to extend down between said walls.
- 40 7. A construction of the character described, consisting of a concrete base and reinforced concrete studding whose lower ends are embedded in said base, said studding being spaced apart, metallic rods extending through the studding and having nuts threaded thereon which abut against each studding on each side and by means of which said studding may be adjusted and fixed in position relative to each other, each side of each studding being provided with two lengthwise extending grooves, spaced apart, the grooves of each studding being arranged in a corresponding position to the grooves of the facing side of the other studding, wall slabs whose ends are shaped to conform with said grooves and fit into the corresponding grooves of the studding so as to form a double wall, the space between the slabs which form the base of the wall being filled with concrete.
8. A construction of the character described, consisting of a concrete base and concrete studding arranged at a suitable distance apart and whose lower ends are embedded in said base, rods extending through the studdings and having adjustable securing members thereon which abut against each studding on each side and by means of which said studdings may be adjusted and fixed in position relative to each other, the sides of the studding facing each other having corresponding lengthwise grooves, wall slabs whose ends are shaped to conform to the shape of said grooves, each slab being of such a length that when one end thereof is completely fit in its groove, the other end thereof may be brought into alinement with the corresponding groove of the other studding, and the slab then moved lengthwise until the last mentioned end will engage in its corresponding groove, thus providing a space between the ends of the slabs and the bottom of the corresponding grooves, and a cement filler in said space in said grooves.
9. A construction of the character described, consisting of a concrete base, upright studding arranged at a suitable distance apart and whose lower ends are embedded in said base, rods extending through the studdings and having adjustable securing members thereon which abut against each studding one on each side and by means of which said studdings may be adjusted and fixed in position relative to each other, the said studding extending from the bottom to the top of the wall and the sides of the studding facing each other having corresponding lengthwise grooves and wall slabs whose ends are shaped to conform to the shape of said grooves, each slab being of a sufficient length to extend from one studding to the other and whose opposite ends fit into the corresponding grooves of said studding and interlock therewith.

In testimony whereof I have signed my name to this specification in the presence of two subscribing witnesses.
